US00D684530S

(12) **United States Design Patent**
Moon et al.

(10) **Patent No.:** US D684,530 S
(45) **Date of Patent:** ** Jun. 18, 2013

(54) **BATTERY**

(75) Inventors: **Dae-Yon Moon**, Yongin-si (KR);
Sang-Jin Park, Yongin-si (KR)

(73) Assignee: **Samsung SDI Co., Ltd.**, Yongin-si (KR)

(**) Term: **14 Years**

(21) Appl. No.: **29/417,928**

(22) Filed: **Apr. 10, 2012**

(30) **Foreign Application Priority Data**

Oct. 12, 2011 (KR) 30-2011-0042372

(51) **LOC (9) Cl.** **13-02**

(52) **U.S. Cl.**

USPC **D13/103**

(58) **Field of Classification Search**

USPC D13/102–106, 110, 118–119, 184;
429/96–100, 163, 176

(57) **CLAIM**

The ornamental design for a battery, as shown and described.

DESCRIPTION

FIG. 1 is a front perspective view of the battery;
FIG. 2 a front elevational view thereof;
FIG. 3 is a rear elevational view thereof;
FIG. 4 is a left side view thereof;
FIG. 5 is a right side view thereof;
FIG. 6 is a plan view thereof;
FIG. 7 is a bottom view thereof; and
FIG. 8 is a reference expanded view of portion A of the battery
shown in FIG. 4;
FIG. 9 is a reference expanded view of portion B of the battery
shown in FIG. 5;
FIG. 10 is a reference expanded view of portion C of the
battery shown in FIG. 6;
FIG. 11 is a reference expanded view of portion D of the
battery shown in FIG. 6; and,
FIG. 12 is a reference expanded view of portion E of the
battery shown in FIG. 7.
